UNITED STATES PATENT OFFICE

MARK A. DEFIBAUGH, OF PEORIA, ILLINOIS, ASSIGNOR TO ALTORFER BROS. COMPANY, OF PEORIA, ILLINOIS, A CORPORATION OF ILLINOIS

WASHING MACHINE

Application filed December 22, 1926. Serial No. 156,299.

This invention relates to washing machines, and especially to washing machines having combined therewith a centrifugal extractor or drier.

5 One of the objects of the invention is in the provision of a combined washer and centrifugal extractor, the same being structurally associated in such manner as to lessen, to a considerable degree, not only the 10 overall dimensions of the machine, but also even more perceptibly the length thereof.

Another object is in the provision of a combined washer and centrifugal drier or extractor, the tub and drier being associated 15 in a manner that the overall dimensions of the machine are considerably lessened by seating the extractor or drier in a concave seat provided in the wall of the tub in a manner to affect very slightly the efficiency 20 of the operation and disposing the centrifugal drier therein.

Still another object is in the provision of a combined washer and centrifugal drier or extractor, the washer having substantially 25 vertical side walls and one of said walls having a concave seat adapted to receive therein the centrifugal drier and casing therefor, with the result that the length of the machine is lessened to a considerable degree.

30 Yet another object is in the provision of a combined washer and centrifugal extractor, said machine being fashioned in a unitary manner, and with a single integrally formed top portion for both the washer and 35 the centrifugal drier, said top portion being connected with the supporting structure with the result that a compact and sturdy machine is presented with a consequent perceptible decrease in the vibration thereof 40 that attends the washing and drying operation.

A further object is in the provision of a combined washing machine and centrifugal drier, the same being assembled as a unitary 45 structure with an integrally formed top member connected to a common supporting means and leg structure, the driving means for the washer and centrifugal drier being so associated with said elements and so connected to the supporting structure as to ut-

ilize the combined weight to diminish the vibration that normally attends the operation of the centrifugal drier.

A still further object is in the provision of a combined washer and centrifugal drier, 55 wherein said elements are assembled and driven with common supporting and driving mechanism, the weight of the supporting means for the driving mechanism being so associated with the common support as 60 well as the combined washer and drier as to distribute the vibration of the centrifugal extractor throughout the whole machine rather than to localize it in the extractor assembly, thereby diminishing such vibration to a minimum. 65

Other objects will appear in the following specification, taken in connection with the annexed drawings, in which—

Fig. 1 is a perspective of the combined 70 washer and centrifugal extractor, portions thereof being either removed or shown in dotted lines for a clearer disclosure of the manner of inseating the tub and the manner of employing a common and unitary supporting structure for the washer and drier; 75 and

Fig. 2 is an enlarged detail, partially broken away, showing the specific manner of inseating the extractor casing and 80 extractor in the wall of the tub.

In the drawings, I have disclosed but generally the combined washer and centrifugal extractor and have omitted, to a considerable degree, operating portions thereon 85 for the sole purpose of emphasizing various features of the device, the same having been set out fully in the statements of the invention.

Other applications are copending which 90 are directed specifically to my special centrifugal extractor, driving means therefor and other structural elements which have purposely not been shown herein; such applications bear Serial Numbers 156,300 and 95 157,088 allowed October 7, 1930, and November 14, 1930 respectively.

Referring specifically to the drawings, there is disclosed a washing machine tub 100 which is designated 10, said tub having a

substantially rectangular shape, with vertical side walls. Said tub is of the general type wherein some form of agitator member, not shown, is disposed in the bottom 5 thereof and driven from below by appropriate driving mechanism, the details of which have been shown and claimed in the above mentioned co-pending applications and which form no part of the present invention.

10 The tub 10 has disposed adjacent thereto a centrifugal extractor or drier, designated 11. This centrifugal extractor comprises a downwardly tapered, imperforate, sheet 15 metal basket, which is adapted to be rotated by a driving means, not shown, disposed therebelow. The centrifugal extractor, or basket 11 is completely surrounded by a similarly tapered casing 12, said casing 20 being connected at its upper end to a fluid chamber 13, which surrounds the upper end of the basket 12 and is adapted to receive the fluid discharged by the centrifugal action of the extractor during rotation.

25 One side wall of the tub 10 is provided with a concave seat 10a preferably slightly off-set from a line passing medially transversely through the longitudinal axis of the tub and such side wall, see Fig. 1, which 30 positions the axis of the extractor or drier 11, seated therein, not only closer than is usual to the axis of the tub, but in close relation to the working side of the machine, whereby the extractor or drier is positioned 35 for convenient use by an attendant and for the more convenient transposition of clothes or other materials from the tub to the extractor or drier and from the latter to a rinse tub or other receptacle; thus reducing considerably the working length or 40 width of the machine. Such seat 10a, as will be understood from the disclosure, is disposed vertically in the wall of the tub and providing or forming such a seat as 45 will receive both the casing 12 and the extractor or drier 11 therewithin; the wall of the tub forming such seat 10a is inclined downwardly and outwardly, or tapered downwardly from the top of the tub to the 50 bottom thereof, conforming substantially to the inclination of the walls of the casing 12 and the extractor 11, as best seen in Fig. 2.

The fluid chamber 13 not only forms a 55 means for attachment for the casing 12, but also a connecting means between the washing machine tub 10, the centrifugal extractor assembly and the common support for the combined unit. As may be clearly seen in 60 Fig. 1, the fluid chamber 13 comprises also the top 14 of the washing machine tub, to which it is riveted in the manner shown at 15. By forming the fluid chamber and top 14 of the tub 10 in an integral manner, it is 65 permitted to tie up the extractor assembly

with the washing machine by connecting said single unit top with the supporting structure for the combined units, said support including the two legs 16 and 17, which are secured at their upper ends to the tub 70 in the manner shown at 18, and the third support and leg 19, which is fixedly connected to the fluid chamber, as shown at 20. It is apparent that the three supporting members which also form the leg portions, 75 are securely united, either directly with the integrally formed single unit top, as shown at 20, or substantially directly as shown at 18.

This attempt to provide a unitary structure of the combined devices is still further assisted by tying together the three supports by the three brace members 21, 22 and 23. The combined units are now connected in an integral manner at the top, as well as in a fixed manner therebelow. This combining of the two units by distributing the weight over a common supporting structure permits the suspension of the driving means which, as far as outward appearances are concerned, includes the electric motor 24 and the gear or driving mechanism housing 25 below the washing machine tub and the centrifugal extractor. In order to make use of the weight of these elements, they are hung below the washing machine tub and are supported at the opposite end by being attached, as at 26, to the vertical support 19.

It is thought apparent from the above that the present peculiar unitary structure permits such disposition of the weighted driving mechanism as to utilize same in a manner to distribute the vibration of the excessively high speed centrifugal extractor throughout the entire machine and not to localize same, as has been heretofore done, solely or substantially so, in the centrifugal extractor or drier itself.

Inasmuch as the present application is directed rather specifically to the general structural assembly that comprehends the combination of a washing machine and centrifugal drier and to the seating of the drier in a seat in the wall of the tub, and thereby reduce the overall dimensions and decrease the length of the machine, a detailing of the operation of the machine is not thought necessary other than to say that the washing is adapted to be done in the tub and the drying in the centrifugal extractor, the washed clothes being placed in the basket 11 and the moisture therein extracted by the centrifugal action during the rotation thereof, the tapering of the basket forcing the extracted fluid upwardly and out of the basket. It is thought apparent that the in seating of the tub permits a considerable reduction in the size of the machine without interfering perceptibly with the operation 120 125 130

of the washer or the efficiency thereof, and that the integrally formed top portion and unitary structure assembly, with the disposition of the weighty driving mechanism below the washer and centrifugal drier and connection of same with the unitary support, results in the distribution of the vibration that attends the centrifugal extractor throughout the whole machine.

With respect to the fashioning of the combined washer and centrifugal extractor, it will be noted that the combined washer and centrifugal extractor are assembled in such manner that the width of the machine is exactly the same as a conventional washing machine, and while the overall dimensions are somewhat greater, nevertheless there is presented one straight side to permit ready placement of the machine in a comparatively small area. In addition, the straight side permits immediate adjacency of rinse and bluing tub, wherein, after the rinsing operation has been completed, the machine may be moved into position that the drier section may be brought into adjacency with respect to the bluing tub.

What I claim is:

1. In a device of the type set forth, a main receptacle, having a concave seat, a secondary receptacle having a part thereof conformably engaged in said seat, a unitary top plate common to and overlying both of the receptacles and having openings therein for access to the respective receptacles, means to rigidly secure the top plate to each of the receptacles, a pair of legs secured to the main receptacle, a single third leg secured to top plate beyond the secondary receptacle and at a point diametrically opposite to the seat, and means connected to the main receptacle and to the third leg and connected to the bottom of the secondary receptacle.
2. In a device of the type set forth, a main receptacle, a secondary receptacle secured to the main receptacle, a unitary top plate common to and overlying each of the receptacles and having openings communicating with the respective receptacles, means to rigidly secure the top plate to each of the receptacles, a supporting structure having connection with the bottom of the main receptacle and having a part connected to one end of the top plate, and means secured to the bottom of the main receptacle and to the bottom of the secondary receptacle and connected to said part of the supporting structure which is connected to said top plate.
3. In a device of the type set forth a main receptacle having a concave seat in a wall thereof, a secondary receptacle conformably engaged in said seat, a unitary top plate common to and overlying each of the receptacles and having openings commu-

nicating with each thereof, means to rigidly secure the top plate to each of the receptacles, and a supporting means for the structure connected to the bottom of the main receptacle and connected to the top plate at a point beyond the secondary receptacle and diametrically opposite to the seat.

4. In a device of the type set forth, a main receptacle having a concave seat in a wall thereof, a secondary receptacle conformably engaged in said seat, a unitary top plate for the receptacles common to and overlying each thereof, and having openings communicating with each receptacle, means to rigidly connect the top plate to each receptacle and a supporting means connected to the bottom of the main receptacle and to the top plate.

In testimony whereof, I have hereunto affixed my signature.
